ROY J. POMEROY, OF LOS ANGELES, CALIFORNIA

SYSTEM FOR CORRECTING SOUND RECORDS

Application filed May 22, 1928, Serial No. 279,790. Renewed March 13, 1931.

This invention relates generally to sound records, and is particularly concerned with methods of perfecting the reproduction of sound. This case is a companion to my application entitled "System for correcting sound records," Serial No. 279,789, filed on even date herewith, and is directed to the same general subject-matter. The substance of the present application may be considered as a variation of the specific steps of the method and system disclosed by the said companion case, the broader claims generic to the common general method being found appended to that case.

As set out in the above mentioned companion case, the invention is broadly applicable to any record of sound vibrations, but is probably most conveniently illustrated and described in connection with the photographic type of record. The particular type of photographic record with which I have chosen to illustrate the invention consists of a shaded band of constant density, a wavy outline representing the sound character and volume. Such records, as well as their method of recording and reproduction, are well known and need no particular description here.

In reproducing sound from these records, distortion is always introduced by the various units involved, this effect usually being due chiefly, however, to the speaker unit. Recording systems may be constructed and balanced so as to introduce only a negligibly small distortion at most, and the main concern is therefore to eliminate the distortions of reproduction. The chief concern is therefore with the distortions of reproduction.

It may now be stated as a general object of this invention to provide a means for compensating for these distortions so that more perfect reproduction of sound will be obtainable.

The general method provides a method and system for making a distortion corrected record, and this is done by introducing, to the record, correction distortions that are compensatory of, or have a neutralizing effect on, the distortions which are introduced by reproduction. In the aforementioned companion

case, this is specifically accomplished by what may be termed a photographic method, in which an original photographic sound record is made, and then reproduced as sound. The distorted sound thus obtained is photographically recorded, this record being termed a distortion record. A negative of this distortion record is then photographically combined with a negative of the original record to make a correction record, and this correction record is finally photographically combined with an original record to make the distortion-corrected record. In the present method, which may be termed an electrical method, instead of photographically combining original and distortion records, a sound current representing the distortion record is combined with a sound current representing the original undistorted record, and this combination is so effected that the resultant current carries variations which represent only the difference between the two records, or in other words, the distortion. A record of this current may be made upon a film and subsequently printed above an original record, or may be directly made upon the film containing the original record. In either case, the result is a distortion corrected record from which sound may be finally reproduced without the distortions of recording and reproduction.

How this is done will be better understood from the following detailed description of a typical means for carrying out the invention, reference for the purpose being had to the accompanying drawings, in which:

Figure 1 shows a system for making an original photographic sound record and a distortion photographic sound record;

Fig. 2 shows a system for making a photographic distortion correction record;

Fig. 3 shows an original photographic sound record;

Fig. 4 shows a distortion photographic sound record;

Fig. 5 shows a photographic distortion-correction record;

Fig. 6 shows a photographic distortion-corrected record;

Fig. 7 shows a variational system for making a photographic distortion-correction record; and

Fig. 8 shows a system for making a photographic distortion-correction record directly upon a film having an original record.

With reference to Fig. 1 the microphone M1 is connected through the leads 10, 11 to the amplifier A1. Amplifier A1, and other amplifiers to be mentioned, may be any suitable electrical or vacuum tube amplifiers adapted to amplify an audio-frequency electrical current. The output 12, 13 of amplifier A1 is connected to a glow tube G1, or other light varying device before which travels a film 14. A plate having a slit S1 is interposed between the glow tube and the film. A second plate having a slit S2 is positioned opposite the glow tube, and beyond it is a photoelectric cell P1. Leads 15, 16 from the photoelectric cell P1 connect to the switch 17, and from there continue to the amplifier A2. Leads 18, 19, having therein a switch 20, connect the microphone leads 10, 11 with the photoelectric cell leads 15, 16 at a point between the switch 17 and the amplifier A2. The output leads 22, 23 of the amplifier A2 connect to the speaker H. The system of Fig. 1 may be operated in either of two manners, depending upon the positions of switches 17 and 20. The system will first be described with switch 17 closed and switch 20 open, the operation with the switches reversed from these positions being considered later.

Microphone M1 picks up the original sound, a sound current being conducted therefrom by the leads 10, 11 to the amplifier A1, and thence to the glow tube G1, the traveling film 14 taking a positive sound record Po of the original undistorted sound. A positive photographic record, in the terminology herein employed, is the original photographic record obtained in recording sound. A negative record is the reversal of this positive, or in other words is the record which would be obtained by ordinary light printing from a positive record. The record Po actually contains distortions introduced within the recording system, but these are capable of being reduced to negligible proportions by properly designing the recording system, and the distortions of recording may therefore be disregarded for the purpose of the present discussion. Light rays are also transmitted from the glow tube through the slit S2 and affect the photoelectric cell P1. Switch 20 being open and switch 17 closed, modulated sound current from the photoelectric cell is conducted by the leads 15, 16 into the amplifier A2 where they are amplified, the amplifier current passing to speaker H and there being reproduced as sound.

From this point, the description of the various units may be conveniently accompanied by a brief explanation of their opera-

tion within the system, and this plan of exposition will hereafter be followed.

Sound reproduced by the speaker H is picked up by microphone M2, a sound current being conducted therefrom through the amplifier A3, and after amplification being conducted to the glow tube G2 before which travels a film 21. A plate having a slit S3 is interposed between the glow tube and this film. The film 21, which travels at a speed synchronous with that of film 14, thus takes a positive sound record Pd identical with the positive sound record Po upon film 14 but with the addition of the distortions introduced in reproduction, and also with the relatively negligible recording distortions of the system M2, A3, G2, S3. The reproducing system P1, A2, H, must be one having identical characteristics with the one which is to be used in final reproduction, and the recording system M2, A3, G2, S3 is one having identical characteristics with the original recording system M1, A1, G1, S1, or one introducing little or no distortion. While it was stated above that a positive record Pd is obtained upon film 21 in the system of Fig. 1, whether a positive or a negative is actually obtained depends upon several factors, such as the polarity of the photo-electric cell P1 and microphone M2 with respect to their amplifiers. To avoid confusion the systems will therefore be assumed in all cases throughout the specification, unless otherwise stated, to be so arranged that a sound wave representation passes through the system without reversal from a positive sound record representation to a negative sound record representation, or vice versa. It will be understood, however, that the steps of the method may easily be varied by such reversals and by corresponding variations in the printing operations, as hereinafter indicated. All such variations, of course, lie within the scope of my invention.

While the records Po and Pd are produced simultaneously in the system of Fig. 1, in effect, the making of Pd is the same as if it were made by reproduction of Po.

In Fig. 3 is shown the film 14 with the original sound record Po having a wavy outline 30, the record being shown greatly enlarged for the purpose of expressing more clearly the various relations between the records. A record of a continuous uniform sound is chosen for representation in the diagram merely for the sake of simplicity of illustration, it being understood that the method applies in the same manner to the record of a complex sound wave. In Fig. 4 is shown the film 21 with the record Pd. This record is similar to Po, but has imposed upon it all of the distortions introduced in reproduction, those relatively insignificant distortions of recording being neglected. The record Pd is hereinafter referred to as the distortion 130

record, and its outline 31 as the distorted curve. This distorted curve 31 is shown superposed in dotted lines upon the positive record P_o in Fig. 3, and it will be seen that 5 the distortion introduced in the reproducing system at any point in the record is represented by the difference in ordinates of the curves 30 and 31.

Whether the amplitude of the distorted 10 curve 31 is greater or less than that of the original curve 30 depends upon the characteristics of the reproducing units, and in any specific case may depend upon the varying factors of sound character. For instance, 15 at one frequency, the distorted curve 31 may be of a greater amplitude than the original curve 30, at another frequency it may be less, while at some intermediate frequency the curves may coincide, indicating that at this 20 frequency no distortional effect is obtained. For the sake of simplicity, only the case in which the distortion effect causes an increase in the sound wave amplitude is illustrated in the drawings. It will later be apparent that 25 although the distortion might equally as well cause a decrease in amplitude, the operation of the system is similar in either case, and therefore, for the sake of simplicity of explanation, the operation will be explained 30 with reference to the aforementioned arbitrarily chosen case; it being understood that the total resultant distortion introduced in reproduction may cause either an increase or a decrease in the amplitude of the sound 35 wave, and that the system corrects the record in either case. In other words, the distortion may be either minus or plus with respect to the original record.

The positive record P_o is next to be artificially modified by the relative addition of opacity at those points at which the distortion is relatively minus, or at which the distorted curve 31 falls below the original curve 30, and by the relative subtraction of opacity 45 at those points at which the distortion is relatively plus, or at which the distorted curve 31 rises above the original curve 30, the amount of this modification at any point being always equal to the distortion at that 50 point. A simple manner of viewing these relations is that the modified record is to be made relatively as much more opaque than the original record as the distortion record is less opaque than the original record, and 55 vice versa, as the case may be.

If then this modified record is run through a reproducing system having the same characteristics as the one utilized in making the modified record, the distortions introduced 60 by that system will again be added and subtracted in the same sense or directions as before; but now the reproducing system causes the sound wave of the modified record to be altered within the system to the shape and proportions of the original wave, and distor-

tionless audible reproduction of the original sound is obtained.

The method of doing this will now be described, and reference for this purpose will be had to Fig. 2. Film 14 with the original sound record P_o is run through a system consisting of an illuminant I and slit 42 on one side of the film, and a photo-electric cell 42 on the other side. Film 21 with the sound record P_d is run through an identical system, consisting of illuminant I' , slit 43 and photo-electric cell 44. These two systems must be matched to have substantially identical characteristics, and the films 14 and 21 must be synchronously driven. The photo-electric cells 42 and 44 are then differentially connected by the leads 45 and 46, so that the current flowing in circuit 45, 46 is the difference of that generated by the photoelectric cells 42 and 44, and therefore represents the difference in the records P_o and P_d , or in other words the distortion. For the purpose of relatively balancing potentials, as will later be more fully explained, potentiometers 55 and 56 are provided across the photo-electric cells 42 and 44, respectively. In series with circuit 45, 46 is a circuit 47, 48 leading to the amplifier A4, the output current of which is conducted to a glow tube 49 and photographically recorded upon the film 50, a slit 51 being provided between the film and the glow tube. A distortion-correction record C, shown in Fig. 5, is thus obtained, the outline 52 of which represents the distortion.

With the system in balance, the differential distortion-current flowing in the circuit 47, 48 into amplifier A4 is a wavy outlined alternating current. The output of the amplifier A4 then consists of a direct current with an amplification of the wavy outline of the distortion current impressed upon it. It will thus be apparent that whether a peak or a depression in the final output current wave, and correspondingly in the correction record C, results from any particular half-cycle of the amplifier input distortion-current depends upon how the leads 47 and 48 are connected into the amplifier A4. Arbitrarily choosing for illustration the case in which a peak in the correction record C corresponds to peaks in the original and distortion positives P_o and P_d , as clearly shown in Figs. 3, 4 and 5, a film 53 is then printed along one edge with a negative correction record C' of the record C just obtained, and with the original positive P_o along the other, as shown in Fig. 6, care being taken that the two prints, the original record and the correction record, are accurately registered with each other.

In case the amplifier input leads are reversed from this arrangement, the negative correction-record C' is obtained directly, and may be printed directly with an original record P_o , as in Fig. 8. The system there shown is similar to that of Fig. 2, but may be con-

sidered as having its input leads reversed from the arrangement of Fig. 2, as above stated, thus giving the negative C' rather than the positive C. In the case illustrated, the correction record C is made directly upon film 53, this film having a previously printed original record Po. Or, if desired, record C' may be made upon a blank film, and by subsequent printing operations, later combined with an original record Po.

As the sound character is determined solely by the outlines of the records, the two records may be laterally positioned upon the single film in any convenient manner which insures absence of overlapping.

We have now added to the original record a correction band of opacity which varies in width by the amount of the distortions, and in a direction or sense negative to that of the 20 distortions. Stated with reference to Fig. 3, we have relatively added opacity by the amount of the distortions where the distorted curve 31 falls below the original curve 30, and relatively subtracted opacity by the amount 25 of the distortions where the distorted curve 31 rises above the original curve 30. Another manner of expressing this is that we have relatively added opacity to the original record by the amount of and negatively to the sense 30 of the distortions.

The result of running the distortion-corrected film 51 through the reproducing system will then be that the distortions inherently associated with the reproducing system 35 will act to correct the sound waves represented by this oppositely distorted record, changing them back to the original wave shape and proportions, and thus the original audible sound is reproduced without distortion.

In order that the above system be operative, it is essential that the amplifiers of the recording and reproducing systems of Fig. 1 be so potentiated or balanced against one another that the sound currents obtained from the records Po and Pd in the correction record making system of Fig. 2 will at any point be of the same magnitudes, except for the distortional difference between them, and will 45 therefore exactly neutralize one another except for this distortion-representing current. This balancing may be accomplished as follows: In the recording and reproducing system of Fig. 1, there will be at least one frequency of sound current at which no distortion will be introduced in reproduction. This frequency being ascertained, it is induced in the system, and the system is then balanced and permanently set at potentials which will 55 give identical records Po and Pd under those conditions of current frequency. With the system so balanced, a sound current of any frequency at which distortion is introduced will make a record Pd exactly like the original 60 undistorted record Po except for the distor-

tions, and the currents represented by these records when differentially combined will be exactly and perfectly neutralized except for the distortion current. In case the balancing of the above system is not quite perfect, the 70 system of Fig. 2 may be utilized to complete the matching of sound currents. For this purpose records Po and Pd are made at the above mentioned frequency at which no distortion occurs, and these are reproduced as 75 sound currents in the system of Fig. 2. If the entire system is in balance, there will be no resultant current in the circuit 45, 46 and no further adjustment is necessary. If, however, the balancing is not perfect, it may 80 be made so by adjusting the potentiometers 55 and 56 in the circuit 45, 46 until the resultant current is reduced to zero. The system is then in balance and readiness for operation. The test for this condition is that 85 there shall be no sound current in the circuit of glow tube 49.

The system has so far been described as compensating solely for the disabilities of reproduction; but the system actually compensates for the relatively small disabilities of recording as well, as will now be pointed out. Starting at the microphone M1 in Fig. 1, the sound wave representation, after passing through amplifier A1 and being transformed from a modulated electric current to modulated light waves, has become distorted by the elements of the recording system, and the original sound record Po therefore contains these distortions. The sound current 100 picked up by the photo-electric cell P1, which current also has these recording distortions, is passed through the amplifier A2 and, with the additional distortions of reproduction, is reproduced as sound. The distorted sound 105 is then picked up by the microphone M2, passed through amplifier A3, and, with the additional distortions of the recording system, is recorded. The record Pd thus contains the distortions of the original record- 110 ing, the distortions of reproduction, and the distortions of the second recording; while the record Po contains only the distortions of the original recording. The differential correction record C made from these two 115 records then contains their difference, or the distortions of recording plus the distortions of reproducing; and the record Po modified by the record C' is therefore corrected for the recording distortions which it contains and 120 also for the reproduction distortions which will be introduced in subsequent reproduction. Both the recording and reproducing systems utilized to modify the record must of course, be the same, or have identical characteristics, as the ones used originally in recording and in finally reproducing the sound.

In case the recording distortions are negligible, the system may be simplified by utilizing an arrangement such as is obtained in 130

the system of Fig. 1 by opening switch 17 and closing switch 20, the sound current being then taken directly from microphone M1 to the reproducing system A2, H. The system and method is otherwise identical with that previously described. In this case no correction is made for the units A1, G1, and P1, their distortions being regarded as relatively insignificant.

- 10 16 If desired, instead of making P_o and P_d originally, record P_o may be made originally, and by properly passing it before the photo-electric cell P1 of the system of Fig. 1, it may be reproduced as a sound current, 70
18 amplified, and photographically recorded. That the record so obtained be a positive P_d , the polarity of the photo-electric cell P1 may be reversed with respect to its amplifier from its arrangement in the system of Fig. 20
20 1. Or a negative of positive P_o may be passed before the photo-electric cell to give the positive P_d . Other variations designed to produce positives P_o and P_d for use in the system of Fig. 2 (or corresponding negatives, 80
25 which are equally adapted) will be readily apparent.

It will now be shown how certain of the steps may be eliminated, reference for this purpose being had to Fig. 7. The circuit here shown has parts similar to that shown in Figs. 1 and 2, and like parts of the systems are therefore indicated by like numerals. Leads 60 and 61 are connected from the output leads 12, 13 of amplifier A1 to the output 85
35 leads of amplifier A3, and these leads are differentially connected so that, except for the distortion-current, the sound currents in circuit 60, 61 are neutralized. Potentiometers 64 and 65 are connected in this case across 90
40 the outputs of amplifiers A1 and A3 respectively for the purpose of balancing the amplifier potentials, similarly to the manner previously explained.

In series with circuit 60, 61 are leads 62, 45 63 leading to the amplifier A4, the output of which connects to the glow tube 49, as before. A correction record C is thus directly obtained upon the film 50 simultaneously with the making of the original record P_o , thus doing 50
55 away with the necessity for making record P_d . A negative correction record C' of this record C is then printed with the original record P_o , as before. Or the system may easily be arranged (by merely reversing the 60
65 input leads to A4, for instance) to give the correction record C' originally, and by then properly positioning glow tubes G1 and 49, original record P_o and correction record C' may be originally and simultaneously printed 66
70 in proper register upon a single film, thus giving the distortion corrected record at once.

The invention has thus far been described as correcting for or compensating the distortions occurring in the simple recordation 65
85 and reproduction of any typical sound rec-

ord. The broad invention, however, has numerous applications in furtherance of this specific use. For instance, it may be embodied as applied to a correction of the distortion effects otherwise unavoidably introduced in 70
75 radio broadcasting. For this purpose, sound would be broadcast from sound records in which compensation has been made for the distortions introduced in their making and reproduction, and also for the distortions introduced by the radio broadcasting set, and by the average radio receiving equipment.

While I have illustrated the invention with the aid of a constant density, variable outline sound record, it will be apparent that the essence of the invention is not limited to the relative addition and subtraction of bands of varying width, but may be considered, when applied to photographic records, as involving the addition and subtraction of 80
85 opacity, and therefore any type of photographic sound record is responsive to the method. In its broadest aspect, in which is embraced all forms of sound records, it may be considered as involving the altering of the 90
95 elements making up the original sound record by the relative addition of correction distortions in the amount of, and in an opposite sense to, the distortions introduced in recording and reproduction.

It will be understood that the foregoing drawings and description are merely illustrative of and not restrictive upon the invention in its broadest sense, for various changes in the specific method and system may be made 100
105 without departing from the spirit and scope of the broader claims appended hereto.

I claim:

1. The method of modifying sound records that includes, making an original record of 105
audible sound, audibly reproducing the sound with the distortions of reproduction, making a distortion record of the distorted sound as so reproduced, synchronously producing electrical sound currents from the 110
original and the distortion records, differentially combining the sound currents so obtained in such a manner that the sound currents are neutralized except for a distortion-representing current, making a correction 115
record of the distortion-representing current, and making a distortion-corrected record by modifying the original record with the correction record in such a manner as to alter the original record by the amount of and in 120
a sense opposite to the distortions introduced in reproduction.

2. The method of modifying sound records that includes, making an original photographic sound record, audibly reproducing 125
sound with the distortions of reproduction, making a photographic distortion record of the distorted sound as so reproduced, synchronously producing electrical sound currents from the original and the distortion 130
record.

records, differentially combining the sound currents so obtained in such a manner that the sound currents are neutralized except for a distortion-representing current, making a photographic correction record of the distortion-representing current, and making a photographic distortion-corrected record by modifying the original record by the correction record in such a manner as to add opacity to the original record varying in quantity by the amount of and in a sense negative to the distortions introduced in reproduction.

3. The method of modifying sound records that includes, simultaneously, making an original photographic sound record, audibly reproducing sound with the distortions of reproduction, and making a photographic distortion record of the distorted sound as so reproduced; synchronously producing electrical sound currents from the original and the distortion records, differentially combining the sound currents so obtained in such a manner that the sound currents are neutralized except for a distortion-representing current, making a photographic correction record of the distortion-representing current, making a photographic distortion-corrected record by modifying the original record by the correction record in such a manner as to add opacity to the original record varying in quantity by the amount of and in a sense negative to the distortions introduced in reproduction.

4. The method of modifying sound records that includes, making an original photographic sound record, audibly reproducing sound with the distortions of reproduction, making a photographic distortion record of the distorted sound as so reproduced, synchronously producing electrical sound currents from the original and the distortion records, differentially combining the sound currents so obtained in such a manner that the sound currents are neutralized except for a distortion-representing current, making a photographic correction record of the distortion-representing current, making a photographic distortion-corrected record by printing a film with an original record and with the correction record, in a manner that opacity is added to the original record in a quantity varying by the amount of and negatively to the sense of the distortions introduced in reproduction.

5. The method of correcting sound records that includes, producing an electrical sound current from the original sound, making an original photographic sound record from the sound current, audibly reproducing sound corresponding to the said sound current, this sound having the distortions of reproduction, and making a photographic distortion record of the distorted sound as so reproduced, synchronously producing sound currents from the original and the distortion

records, differentially combining the sound currents so obtained in such a manner that the sound currents will be neutralized except for a distortion-representing current, making a photographic correction record of the distortion-representing current, making a photographic distortion corrected record by printing a film with an original record and with the correction record, all in a manner that opacity is added to the original record varying by the amount of and negatively to the sense of the distortions introduced in reproduction.

6. In a system for correcting sound records, means for producing an original electrical sound current from the original sound, photographic sound current recording means actuated by the said original sound current, means for reproducing sound with the distortions of reproduction from the sound current, means for producing a distorted electrical sound current from the distorted sound, photographic sound current recording means actuated by the said distorted sound current, means for producing a distorted electrical sound current from the distortion photographic sound record so produced, means for producing an electrical sound current from a photographic sound record made of the original sound current, means for differentially combining the last mentioned sound current with the above said distorted sound current produced from the distortion record in such a manner that the parts of the sound current waves representing the original sound are neutralized leaving a distortion-representing electrical current, and photographic means for recording the distortion-representing current.

In witness that I claim the foregoing I have hereunto subscribed my name this 24th day of March, 1928.

ROY J. POMEROY.
